UNITED STATES PATENT OFFICE.

ARMAND DUCHEMIN, OF PARIS, FRANCE.

APPARATUS FOR THE MANUFACTURE OF CYANAMID.

1,363,096.

Specification of Letters Patent. Patented Dec. 21, 1920.

Application filed July 15, 1919. Serial No. 311,109.

To all whom it may concern:

Be it known that I, ARMAND DUCHEMIN, citizen of the Republic of France, and residing at Paris, France, have invented improvements in Apparatus for the Manufacture of Cyanamid, of which the following is a specification.

The manufacture of cyanamid by the processes at present in use is effected by placing calcium carbid previously ground in an atmosphere of nitrogen and heating it by means of carbon rods through which an electric current is passed. As the carbon rods oppose a high resistance to the passage of the current through them, they are brought to incandescence and heat a portion of the carbid to a red heat, thus starting the reaction which is then maintained by the heat produced by the formation of nitrogenated lime.

This method of operation presents a number of disadvantages:

1. The nitrogen does not penetrate into the mass except in proportion to its absorption by the carbid; the inert gases introduced with the nitrogen, argon, neon and so forth, as also those formed by the subsidiary reaction are imprisoned in the solidified mass, so that the reaction is stopped before the nitration is complete, and a portion of the carbid is lost, in consequence of the fact that it is no longer in contact with the necessary nitrogen to convert it into cyanamid.

2. The reaction is slow in consequence of the difficulty which the nitrogen meets in penetrating into the solidified mass, the more so as the heat only acts upon a small portion of the carbid mass, this being the only portion which enters into reaction from the start. The reaction proceeds only very slowly from point to point of the whole charge in consequence of the bad conductivity of heat both of the ground carbid and of the cyanamid. Finally, the nitrogen and the inert gases imprisoned expand in consequence of the high temperature to which they are heated, so that at this temperature they occupy a considerably greater volume than they would occupy at the ordinary temperature, and consequently the reaction is slow and increases the mass of carbid which cannot come into contact with the necessary nitrogen to produce a reaction.

3. The electric heating absorbs a very appreciable quantity of electric energy.

The process, hereinafter described, which

forms the subject of the present invention, avoids the disadvantages hereinbefore referred to.

The present invention comprises the following characteristic features:

(a) Instead of allowing the nitrogen to penetrate the mass of ground carbid by simple diffusion, it is forced into this mass and must filter through the latter and drive out the inert gases which it incloses so that all the carbid is brought into contact with an excess of nitrogen which assists the reaction and renders it as complete as possible.

(b) Instead of operating at atmospheric pressure or at pressure very near this latter, the operation is carried out under pressure by providing means for closing the furnace. The rapidity of the reaction is thus increased and intensified. This intensification of reactions by the pressure of gases is employed in a number of chemical industries, and it has been observed that reactions are accelerated nearly in proportion to the square of the absolute pressures and that reactions are more certain to take place, while at lower pressures they cannot be carried out completely, all other conditions remaining the same.

(c) The furnace is provided with a thick lining of bricks of a basic material, for example of magnesia having a density of about 3 with a specific heat of about 0.25, which constitutes a sufficiently good heat regenerator for promoting the reaction of a new charge with the heat produced by the preceding charge.

Heating is effected externally instead of centrally, thus increasing the surface which enters into reaction from the start and consequently accelerating the operation while reducing the cost of heating to promote this reaction.

(d) The nitrogen entering the furnace is heated by circulating between the outer wall and the brickwork before reaching the carbid, which leads to a reduction in the losses in heat of the furnace, protects the covering from the heat and finally assists the reaction by drawing into the interior of the furnace the heat which tends to escape.

(e) When nitrating under pressure, as has been stated above, a number of furnaces can be placed in series for the current of nitrogen, so that this latter may be used more completely and only inert gases with

- the minimum quantity of nitrogen are allowed to escape from the last furnace. This successive utilization of the nitrogen leads to a more efficient circulation of the gases; 5 by making the system of pipes short and well insulated, the internal heat of the furnaces is raised more regularly, which tends to intensify the reaction, thus rendering it more complete.
- 10 In the accompanying drawing is shown, by way of example a constructional form of the apparatus for carrying into effect the process according to this invention.
- This apparatus is provided with a crucible *a* of sheet iron and is adapted to receive the carbid to be nitrated. The crucible has a perforated sheet iron base *b* which supports a layer or covering of asbestos, or also a layer of tough paper, corrugated paper 15 or the like, which once carbonized, will support the carbid. This crucible is inclosed in brickwork *c c'* forming a heat regenerator or accumulator, and an inner air-tight casing *d* around which is placed a covering 20 of fibrous asbestos *e*, serving as a heat insulator and as a distributor for the gases; the whole being placed in a casing *f* composed of sheet iron or of cast iron. *g* indicates a joint between the casing *d* and the 25 outer casing *f* made by a packing of asbestos and sodium silicate; *h* indicates the brackets for holding the upper end of the casing *d* centrally in the casing *f* of the furnace; *i* is an annular joint made of a 30 sheet or layer of asbestos; *j* indicates the carbid to be nitrated; *k* is an extension of the casing *f*; *l* is the furnace cover; *m* is a counterpoised lever which is pivotally mounted and serves to operate the cover *l*; 35 *n* is a tap for reducing the pressure inside the furnace before lifting the cover; *o o* are columns for supporting the furnace; *p* indicates the floor for working the furnace; *q* is a tubular member for the admission of 40 nitrogen into the furnace; *r r* are openings arranged between the bricks for the outflow of the gases; *s* indicates a tubular member for the outlet of the gases; *t* is a plug for the removal of dust; *u* is an opening for 45 the introduction of the blow pipe for heating the furnace at the commencement of working; *v v v* are eyes for use in lifting the crucible *a*; *x* are angle pieces for centering the crucible in the furnace; *y* is the 50 lining of the extension or hood *k*; *z* is a lining of agglomerated and pounded refractory materials. The lever *m* above referred to is so mounted as to enable it not only to be rocked or swung in a vertical 55 plane to raise or lower the cover *l*, but also to rock or swing horizontally, or substantially horizontally, to swing said cover to one side. The said lever is preferably forked at its point of attachment to the 60 cover so as to avoid blocking the blow pipe

opening *u* which, in such case, is disposed between the arms of the fork.

The operation of the apparatus is as follows:

The crucible *a* being in position is filled 70 with very finely powdered carbid *j*.

The nitrogen enters the furnace through the tubular member *q*, rises between the sheet iron casings *d f* passing through the 75 layer of asbestos *e* which controls its circulation over the whole periphery, and then passes through the empty spaces provided for this purpose between the bricks of covering *y*, being heated in its course, and finally reaching the top of the crucible *a*. 80

As the crucible rests with its whole weight upon its even lower surface on the asbestos joint *i*, the nitrogen cannot escape between the crucible *a* and the brickwork *c c'*, so that it must filter through the carbid which 85 fills the crucible.

The hot gases tend to rise, the top of the furnace being hotter than the bottom; but as the nitrogen circulates in descending, the temperature tends to remain uniform in the 90 center of the furnace so that the reaction is kept uniform. The gases after having passed through the carbid, filter through the asbestos disk or the carbon disk formed by the tough paper placed on the perforated 95 iron *b*, and which has been carbonized, and pass through the orifices *r* to the tubular gas outlet *s*. The tubular nitrogen inlet member *q* and the tubular gas outlet member *s* are provided with valves for the purpose of 100 disconnecting the furnace for emptying and recharging.

If it is desired to place a number of furnaces in series it is sufficient to connect the tubular members *q* and *s* of two consecutive furnaces by a system of pipes provided with a central disconnecting valve, and with branch pipes with valves on each side of the valves hereinbefore mentioned, one for the admission of nitrogen and the 110 other for the outflow of inert gases.

For the purpose of regulating the pressure of the furnace the outlets for nitrogen from the furnaces are connected together to a gas holder with a safety valve for limiting 115 the pressure.

The type of furnace hereinbefore described may be of any suitable dimensions and it may be of any suitable shape or proportions; the crucible may be omitted, the 120 carbid in this case resting on a base which can be connected to one heat retaining lining. The heat regenerator may be of any suitable material such as bricks, metal and so forth. The furnace may be rigid or it 125 may be pivotally mounted for discharging purposes.

All the parts forming the furnace may be of any suitable material without modifying the principle of the system of nitration. 130

Instead of promoting the reaction either by direct heating or by the regeneration of the heat produced by the preceding operation and absorbed by a suitable furnace lining, this promotion can be produced by utilizing the heat evolved by the reaction of two solid bodies more or less finely pulverized and capable of reacting one upon the other without the formation of a considerable gaseous mass.

For this purpose it is possible for example to use the reaction which is produced when mixing together an alkali metal, an alkaline earth metal or the like (potassium, sodium, calcium, magnesium, aluminium, and so forth), with an oxid, a chlorid, an iodid, or a bromid of another metal (iron, zinc, copper, lead, and so forth), a reaction which permits of obtaining high temperatures.

The alumino-thermic process already employed for other uses gives one of the mixtures which is suitable for use in obtaining the desired result.

The process may be carried into effect by introducing any suitable receptacle, or a cartridge of suitable size, containing the desired mixture into or on the carbid in the crucible and starting the reaction or the combustion by any suitable means such as priming, percussion cap or electric current.

I claim:

1. A furnace for the production of calcium cyanamid, comprising, in combination, a central crucible to receive the carbid to be treated and provided with a perforated bottom; a support permeable to gases on said bottom; a fire-brick casing surrounding said crucible but spaced therefrom and forming a heat recuperator; an inner air-tight

metal casing surrounding the fire-brick casing; an outer air-tight metal casing spaced from the inner metal casing and supporting the cover and bottom elements of the furnace; a filling of asbestos disposed in the space between the outer and inner metal casings; a pipe for supplying nitrogen to the lower portion of the furnace between said outer and inner metal casings; and an outlet pipe for the gas connected to the said lower portion of the apparatus.

2. A furnace for the production of calcium cyanamid comprising, in combination, a central crucible to receive the carbid to be treated and provided with a perforated bottom; a support permeable to gases on said bottom; a casing of refractory material surrounding said crucible but spaced from it, and constituting a heat recuperator; an outer metal casing surrounding the entire furnace and supporting the cover and bottom elements of the furnace; a pipe for the introduction of nitrogen to the lower part of the furnace between the recuperator and the outer casing, and a pipe for the discharge of gases likewise disposed at the lower part of the furnace and communicating with the space situated below the support at the bottom of the crucible, the latter resting its whole weight upon the bottom of the furnace; means being provided for forming a tight joint between said crucible and the furnace bottom.

In testimony whereof I have signed my name to this specification in the presence of two subscribing witnesses.

ARMAND DUCHEMIN.
